UNITED STATES PATENT OFFICE

173,017

BATHING CAP

Richard S. Condon, Dover, Del., assignor to International Latex Corporation, Dover, Del., a corporation of Delaware

Application May 14, 1954, Serial No. 30,503

Term of patent 14 years

(Cl. D3—13)

To all whom it may concern:

Be it known that I, Richard S. Condon, a citizen of the United States and a resident of Dover, in the county of Kent and State of Delaware, have invented a new, original, and ornamental Design for a Bathing Cap, of which the following is a specification, reference being had to the accompanying drawings, forming part thereof, wherein:

Fig. 1 is a side view of a bathing cap showing my new design; the side opposite thereto being substantially similar in appearance;

Fig. 2 is a front view of the bathing cap shown in Fig. 1; and

Fig. 3 is a back view of the bathing cap shown in Figs. 1 and 2.

I claim:

The ornamental design for a bathing cap, as shown and described.
